UNITED STATES PATENT OFFICE.

GEORGE E. MOLYNEUX, OF BAYONNE, NEW JERSEY, ASSIGNOR TO THE SINGER.
MANUFACTURING COMPANY, A CORPORATION OF NEW JERSEY.

SEWING-MACHINE GUIDE.

1,225,156.

Specification of Letters Patent.

Patented May 8, 1917.

Application filed July 19, 1915. Serial No. 40,566.

To all whom it may concern:

Be it known that I, GEORGE E. MOLYNEUX, a citizen of the United States, residing at Bayonne, in the county of Hudson and State of New Jersey, have invented certain new and useful Improvements in Sewing-Machine Guides, of which the following is a specification, reference being had therein to the accompanying drawings.

10 This invention relates to improvements in sewing machine guides and has for its object to provide a guide device especially adapted for mechanically abutting the edges of cut knit goods pieces preparatory to the uniting of said abutted edges by the stitch-forming mechanism of the machine.

15 The improvements comprise a combined presser- and guide-foot which coacts with a guide-block adjustably secured upon the throat-plate of the machine. The presser-foot is of increased thickness at its forward or receiving end and is cut away to form two reversely inclined and converging guide-walls, each wall gradually decreasing in height toward its delivery end, the whole forming a substantially V-shaped structure. The guide-block is beveled on its upper face and it is formed with a projecting nose shaped to correspond with the walls of the 20 foot. The guiding surfaces thus described act upon two opposite margins of the fabric piece or pieces to turn them upwardly from the horizontal plane of the body fabric, until the said margins meet in substantially inverted V-shaped formation; and as the 25 fabric is passed through the guide by the action of the sewing machine feed, the walls of the guide serve to gradually decrease the height of the inverted V-shaped formation 30 of the margins until a point is reached where they are ironed flat, and their edges crowded together by the lower face of the foot.

35 The details of the improvements will be readily understood by reference to the accompanying drawings, in which Figure 1 is a perspective view of the improvements applied to a sewing machine, illustrating the manner in which the fabric is presented to 40 the guiding elements. Fig. 2 is a perspective view from the under faces of the foot and block and Fig. 3 is a sectional side elevation of the improvements in connection with the feeding elements of a sewing machine. Fig. 4 is a cross section of the guide 45

elements on the line 4—4, Fig. 3 and Fig. 5 is a cross section of the guide elements on the line 5—5, Fig. 3.

50 The improvements are shown in conjunction with the tubular work-supporting arm A of a sewing machine employing four needles n and a single looper l, the latter being mounted upon the rock-shaft 1 extending lengthwise of the arm A and overlying an endwise movable shaft 2 connected to the looper-carrier 3 for imparting the sidewise movements to the looper. The feed-bar 6 of the machine carries the feed-dogs 7 and 8 and the auxiliary presser-bar 9 carries at its lower end the shank 10 of the 55 combined presser and guide-foot which coacts with the guide-block 12 in guiding the two fabric edges into horizontal abutment.

60 The presser-foot, pivotally connected to its shank by means of the pin 13, is of increased thickness at its forward or receiving end, and is cut away to form two converging guide-walls w, each guide-wall being flared outwardly from a line longitudinally and 65 centrally of the foot and being beveled toward the plane of the throat-plate 17 to form a substantially V-shaped structure both in plan and in cross-section.

70 The guide-block 12 is formed with a slot 75 14, surrounded by a shoulder 15, to receive and provide a seat for the head of a set-screw 16 adapted to hold the block in adjusted position upon the throat-plate 17 of the machine. The guide-block is held 75 against turning by a depending pin 18 fitted within a slot 19 in the throat-plate. The upper face of the guide-block is beveled, and is provided with a projecting nose shaped to correspond with the converging walls of the 80 foot and recessed in its under surface to clear the feed-dog. By moving the block toward or from the guide-foot, the spacing between these two members is adjusted to 85 accommodate the exact thickness of the 85 fabric to be acted upon, so that no excess spacing will permit the margins to curl and the edges will be compelled to crowd together without overlapping.

90 The walls of the guide members hold the 90 margins of the fabric in substantially inverted V-shape formation, as shown in Figs. 4 and 5. As the fabric is passed through the guide by the action of the feed, the guiding walls serve to gradually decrease the 95 100 105 110

degree of the inverted V-shape formation of the margins until a point is reached where they are ironed flat and the edges crowded together by the lower face of the foot.

- 5 By means of the above described improvement, the edges of cut knit-goods pieces may be presented to the stitch-forming mechanism of a sewing machine in abutment without overlapping, so as to render unnecessary 10 the use of a trimmer preliminary to the stitching operation. It will be understood that various changes may be made in the construction and arrangement of the elements above described without departing 15 from the spirit of the invention. For example the guiding element which coacts with the guide-block 12 may be formed separately from the presser-foot of the machine, also the guiding elements may be inverted, if desired without affecting the mode 20 of operation thereof.

Having thus set forth the nature of the invention, what I claim herein is:—

1. In a sewing machine guide, means for 25 guiding the edges of fabric into abutment preliminary to a stitching operation, comprising guiding walls adapted to receive and turn two margins of fabric into substantially V-shape formation and gradually to decrease the degree of such formation. 30

2. In a sewing machine guide, means for 35 guiding the edges of fabric into abutment preliminary to a stitching operation, comprising two separable guiding members co-acting to turn two margins of fabric into substantially V-shape formation and subsequently to decrease the degree of such formation to a point where the said margins are flattened into substantially the same 40 plane.

3. In sewing machine guides, a guide-foot formed with a V-shape channel in its lower face, and a guide-block coacting with said foot, the said block having an upper face 45 the reverse in contour to the lower face of the foot and being adjustable relatively thereto.

4. In sewing machine guides, a guide-foot formed with a V-shape channel in its lower 50 face, and a guide-block coacting with said foot, the said block having an upper face

the reverse in contour to the lower face of the foot and having a portion of its base cut away.

5. In a device for guiding the edges of 55 fabrics into abutting relation and in a compact condition, an upper member having outwardly diverging and downwardly and laterally beveled walls, a lower member having a projecting nose spaced from the walls 60 of the upper member and defining therewith a fabric passage, said passage being inclined downwardly.

6. A presser-foot, downwardly and rearwardly beveled and converging walls defining 65 a V-shaped recess therein, in combination with a mating member having a tapering and beveled end spaced from said foot to form a V-shaped fabric passage therewith and of diminishing dimensions toward 70 the rear of said presser-foot.

7. In combination, a feed-dog, a presser-foot coöperating therewith and means arranged between the edges of said feed-dog and including walls defining a V-shaped 75 and downwardly inclined fabric passage for bringing the edges of goods into abutting relation in a compact condition for stitching, said feed-dog engaging the fabrics before they merge into the plane of the work-support. 80

8. In combination, a presser-foot, a feed-dog having outer members arranged adjacent the edges of said presser-foot, said foot and dog having coöperative work-engaging 85 surfaces, said presser-foot having a V-shaped recess in its front portion, and a beveled and tapering projection extending between the ranges of movement of the outer members of the feed-dog whereby as two pieces 90 of material are fed their edges are arranged in abutting relation and crowded together. 90

9. In a device for guiding the edges of fabric into abutting relation and in a compact condition, two members having spaced 95 walls defining a fabric passage of an inverted V-shape in cross section and downwardly inclined to the horizontal.

In testimony whereof, I have signed my name to this specification.

GEORGE E. MOLYNEUX.
